UNITED STATES PATENT OFFICE.

FAYETTE P. RISDON, OF HOUSTON, TEXAS, ASSIGNOR, BY MESNE ASSIGNMENTS, TO
THE TEXAS COMPANY, OF NEW YORK, N. Y., A CORPORATION OF DELAWARE.

FRACTIONATING APPARATUS.

Application filed August 21, 1924. Serial No. 733,265.

This invention relates to rectifying or fractionating apparatus and more particularly to rectifying towers or columns of the bubble tower type.

5 The apparatus of my invention is well adapted for use in connection with the well known heat and pressure method of cracking hydrocarbon oils, in which pressure is maintained through the separating and fractionating apparatus. The invention is, however, by no means limited to pressure cracking operations, and is in fact applicable to crude distillation or other distilling operations, to gasoline stabilization processes and for various purposes both within and outside of the oil and gas industry, as will readily be apparent from the detailed description of the invention contained herein.

20 One object of the invention is to provide a bubble tower or rectifying or fractionating column in which the shell or drum may be a unitary structure made in one piece or permanently built up of welded or riveted plate, thus making it suitable for use under high pressure.

25 Another object is to provide a sectional or adjustable type of fractionating equipment so that the apparatus may be readily accommodated to varying requirements, while at the same time retaining a unitary construction for the shell of the column or tower so that it will be adapted for use under high pressures. In the furtherance of this object my invention contemplates a plurality of 30 nests or sections of bubble trays, each section comprising a plurality of trays. The several trays are arranged to be readily removable from the apparatus so that the same may be adjusted to the particular requirements desired.

35 A further object is to provide a compact rugged interior construction which shall be composed of readily removable parts adapted to be manufactured in large quantities and to be quickly assembled within a one piece shell of the type above indicated.

40 Other objects and advantages of my invention will be hereinafter brought out and will be apparent to those skilled in the art to which it pertains from the following detailed description of certain specific embodiments of my invention which are included for the purposes of illustration.

In the drawings:—

Figure 1 is a sectional elevation of a bubble 55 tower constructed in accordance with the invention and constituting an embodiment thereof.

Figure 2 is an enlarged section taken on the line 2—2 of Figure 1.

Figure 3 is an enlarged section showing a portion of the bubble tower taken on the line 3—3 of Figure 2.

Figure 4 is a section in detail taken on line 4—4 of Fig. 2 showing a method of securing 65 the bubble caps in the upper trays.

Figure 5 is a section of a bubble cap.

In the drawings 10 represents a shell, which may be composed of one piece of metal or is made up of a number of plates welded or 70 riveted together to form a single unitary structure. 11 designates the vapor line which enters at the lower end of the tower and 12 represents the vapor line for the removal of vapors or gases from the tower. 13 is a 75 pipe or connection for drawing off condensate or liquid that accumulates in the bottom of the column. It is convenient to provide a gauge such as 14 for indicating the liquid level therein. The tower may also be 80 equipped with a suitable means for supplying a reflux liquid thereto and such other accessories as may be desired, which it is unnecessary to describe herein.

85 A plurality of nests or sections of bubble trays 15 are suitably mounted within the tower. Each nest is supported on a flange 16, which is suitably riveted or welded to the shell 10. The several trays of each nest are positioned one above the other in a manner that is hereinafter more fully described. Spaced manways 17 are provided adjacent the several nests so that convenient access may be had to the several trays for the purposes of cleaning, inspection, renewal, etc. 95

90 As more clearly shown in Figures 2 and 3, each of the several bubble trays 15 is composed of a plurality of sections such as 15^a, 15^b, 15^c and 15^d. The contiguous edges of the several sections are formed with ribs 19 100 which not only serve to strengthen the trays but provide means for firmly securing the several sections together as by means of bolts 18. The several sections have arcuate flanges 20 which, when the sections are assembled 105 together, form a complete annular flange or

rim. This rim extends upwardly a sufficient distance to clear the bubble caps, which will presently be described, and also preferably extends slightly below the base of the tray. 5 The top and bottom edges of the rim are preferably machined so as to permit a perfect nesting of the trays when assembled within the tower and so as to form fluid tight joints between the several sections. It is also ad- 10 vantageous to machine the contiguous edges of the adjoining flanges 19 so that when the several sections 15^a, 15^b, 15^c and 15^d are connected together a liquid tight tray will be formed. If desired gaskets may be inter- 15 posed between the connected parts.

The several sections 15^a, 15^b, 15^c and 15^d are formed in sizes that may conveniently be inserted through the manways 17. In this way the several parts of which each tray is 20 composed may be readily passed into the interior of the shell 10 and the trays assembled therein. Whenever it is necessary to remove any of the trays, access may be had to any of the several nests so that it is possible to 25 remove certain of the trays and make replacements without having to disturb the other trays.

Each tray is provided with one or more nipples or connections 28 which serve to reflux liquid from one tray to another. The height of these reflux lines determines the 30 liquid levels in the trays. Each pipe extends from one tray to the adjacent tray underneath to a point below the normal liquid level 35 therein. The nipples 28 may be constructed integrally with the trays or they may, as illustrated, be separable. In the arrangement shown each pipe 28 is formed with a flange 29 by which the pipe is seated on a cooper- 40 ating flange 30 formed in the base of the bubble tray and to which it may be secured as by means of bolts 31. I have shown each bubble tray as being equipped with one reflux pipe, but it is to be understood that if desired, more than one may be employed. 45 Whatever the number used it is preferable to provide the pipes of adjacent trays in staggered relation to each other so as to secure efficient distribution of the downflowing 50 liquid.

The reflux pipes from the bottom trays of the several nests are preferably made with a U bend 32 so as to form a liquid seal therein. If desired, instead of employing a U pipe, 55 each pipe from the bottom tray of a nest may depend into a pocket or gutter suitably mounted within the shell 10. Provision may be made for withdrawing the liquid from the fractionating tower at various points therein, 60 such as at the bottom of each nest or section of bubble trays, or all of the liquid may be allowed to descend through the tower to the bottom thereof.

Each tray is provided with a plurality of 65 risers 21 which constitute conduits for the

vapors or gases passing upwardly through the several trays. It is preferable to construct the risers integral with the trays, as illustrated. Suitable bubble caps 22 are disposed over the several risers 21. While various types of bubble caps may be employed, I have shown, for purposes of illustration, a specific type of cap which has been found satisfactory in use. The cap thus illustrated is provided with a serrated bottom to afford maximum contact between the vapors and the liquid and is formed with a plurality of legs 23 which rest on the bottom of the tray and with interior ribs 24 by which each cap may be seated on the top of a riser 21. 70 75 80

An important feature in the construction of the caps illustrated is the provision of lugs or fingers 25, which prevent the caps from being blown off their seats. It is apparent that any sudden increase in the pressure of the upwardly rising gases cannot force the caps off their seats, since the lugs or fingers 25 come in contact with the bottom of the superposed bubble tray. In order to retain in position the bubble caps of the top trays of each 90 nest or section of trays, suitable cross bars 26 may be provided as clearly shown in Figure 2, and as indicated in Figure 4 the bars may be secured by means of suitable wire or binder 95 100 105 110 115 120 125 130 27 to pins or bolts 18 fixed to the ribs or flanges 19.

Apparatus of preferred form and construction has been illustrated and described for the purpose of showing the way in which this invention may be practiced, but the inventive thought upon which this application is based is broader than the illustrative embodiment thereof, and no limitations are intended other than those imposed by the appended claims.

What I claim is:

1. A bubble tray for a fractionating or rectifying apparatus formed of a plurality of sections having contiguous ribs by which said sections may be secured, and provided with arcuate ribs which when the several sections are united constitute a peripheral rim for the tray.

2. Apparatus for fractionating or rectifying fluids comprising a chamber, a plurality of distilling pans mounted therein, means for refluxing liquid from pan to pan, risers in said pans for conducting vapors thereinto, bubble caps loosely mounted over said risers and means for limiting the movement of said bubble caps.

3. Apparatus for fractionating or rectifying fluids comprising a chamber, a plurality of distilling pans mounted therein, means for refluxing liquid from pan to pan, risers in said pans for conducting vapors thereinto, and bubble caps formed with upwardly extending lugs and adapted to be loosely mounted over said risers.

4. Apparatus for fractionating and rectifying fluids comprising a unitary shell, a plu-

rality of spaced flanges formed in the interior of said shell, a manway positioned above each of said flanges, a nest of bubble trays mounted upon each of said flanges, each of said nests 5 formed of detachable elements of a size capable of being inserted through said manways.

5. A bubble cap for a fractionating apparatus comprising a hollow member having an open bottom formed with serrated edges, 10 and provided with legs extending beyond said edges and provided at the top with an upwardly extending lug.

6. Apparatus for fractionating or rectifying fluids comprising a vertically disposed 15 unitary shell formed with a plurality of vertically spaced manways and vertically spaced interior flanges, and nests of bubble trays

mounted on said flanges, said nests being made up of a plurality of individual trays loosely stacked upon the several flanges. 20

7. Apparatus for fractionating or rectifying fluids comprising a shell, a plurality of spaced flanges disposed interiorly of said shell, nests of bubble trays formed with loosely mounted bubble caps and supported on 25 said flanges, the trays of each nest being superposed one above the other and each bottom tray of which rests on one of said flanges, and means for securing the bubble caps of the top tray of each nest. 30

In witness whereof I have hereunto set my hand this 12th day of August, 1924.

FAYETTE P. RISDON.
